UNITED STATES PATENT OFFICE.

AMBROSE L. SADDLEMIRE, OF KNOX, NEW YORK.

HAME-TUG.

960,114.

Specification of Letters Patent. Patented May 31, 1910.

Application filed August 12, 1909. Serial No. 512,545.

To all whom it may concern:

Be it known that I, AMBROSE L. SADDLEMIRE, a citizen of the United States, and a resident of Knox, in the county of Albany 5 and State of New York, have invented a new and Improved Hame-Tug, of which the following is a full, clear, and exact description.

The invention relates to harnesses, and its object is to provide a new and improved 10 hame tug arranged to insure a straight pull on the hame sticks and without danger of cutting or otherwise injuring the collar.

For the purpose mentioned a metallic clip engages the hame stick and is provided with 15 a transversely extending pivot on which is mounted to swing a metallic end piece of the trace.

A practical embodiment of the invention is represented in the accompanying drawings 20 forming a part of this specification, in which similar characters of reference indicate corresponding parts in all the views.

Figure 1 is a sectional plan view of the hame tug; Fig. 2 is a side elevation of the 25 same; and Fig. 3 is a transverse section of the same, on the line 3—3 of Fig. 2.

The metallic clip A of the hame tug is 30 preferably made from a single piece of sheet metal bent to form an eye A', doubled up members A², A³, offsets A⁴, A⁵, spaced flanges A⁶, A⁷, and lugs A⁸ extending integrally from the doubled up member A² and bent over onto the front of the other member A³ to securely fasten the members A² and A³ 35 together. The eye A' of the metallic clip A engages the hame stick B and is secured thereon by an eye-bolt C to which the pole chain is attached.

By the arrangement described the metallic 40 clip A can be moved up or down on the hame stick B to the proper position to be then fastened in place by the eye-bolt C.

The flanges A⁶, A⁷ are apertured for the 45 passage of a pivot D, preferably made in two parts, of which the front part consists of a head D' and an externally threaded shank D², and the rear part consists of an internally threaded shank D³ and a head D⁴, the shank D² screwing in the shank D³ and 50 the latter fitting the apertures in the spaced flanges A⁶, A⁷. The head D⁴ of the rear pivot member is flush with the doubled up member A² and this head D⁴ is provided with a straight portion D⁵ abutting against

the offset A⁴ to hold the pivot D against 55 turning.

The trace E of leather or other suitable material is provided with a metallic end piece F preferably made of sheet metal and fastened to the trace by rivets G or other 60 fastening means. The piece of sheet metal for forming the end piece F is doubled up to form the doubled up terminal F' having an aperture for the passage of the shank D³ of the pivot D, the said doubled up portion F' 65 extending between the flanges A⁶ and A⁷ of the clip A, as plainly indicated in Fig. 1. The front part of the doubled up portion F' of the end piece F terminates in an offset F² from which extends the terminal F³ fitting 70 onto the front face of the trace E, the rear face of which is engaged by the terminal F⁴ of the rear member of the doubled up portion F'. The terminals F³ and F⁴ are fastened in place on the trace E by the rivets 75 G, or other fastening means, so that the end piece F is securely held in place on the trace E.

By the arrangement described the trace E has a pivotal connection with the clip A to 80 allow an up and down swinging motion of the connected parts, thus insuring at all times a straight pull on the hame stick B.

By reference to Fig. 1, it will be noticed that the inner face of the clip A is curved to 85 properly fit the animal's collar and the head D⁴ is flush with the said inner face of the clip to prevent cutting into the collar, especially as the pivot D is held against turning.

The hame tug shown and described is very 90 simple and durable in construction and the parts can be readily connected with each other and the clip A can be adjusted up or down on the hame stick B to suit existing conditions.

It will be observed that the improved 95 tug consists of a sheet of metal doubled upon itself to form an eye for encircling the hame, the ends of the sheet being offset outwardly from the inner face of 100 the clip and spaced apart from each other, with the trace end inserted between the said spaced ends, and a pivot consisting of inter-engaged sections, each section consisting of a stem and a head, the stem of the inner 105 section being externally threaded, the stem of the outer section being internally threaded and engaging the first named stem, the

2
head of the inner section being flat and flush with the inner face of the clip.

Having thus described my invention, I claim as new and desire to secure by Letters Patent:

1. A hame tug comprising a clip made of a single piece of sheet metal bent to form doubled up members and an eye for engagement with the hame stick, one of the doubled up members having lugs bent onto the other member to fasten the members together, the ends of the doubled up members having outward offsets terminating in spaced flanges, a pivot extending transversely through the said flanges, an end piece on the trace and formed of a single piece of sheet metal bent to form spaced ends, and a doubled up portion extending between the said flanges and engaging the said pivot, the said spaced ends receiving the trace terminal between them, and rivets for connecting the trace ends and the spaced ends.

2. A hame tug comprising a clip doubled upon itself to form an eye for encircling the hame, the ends of the clip being offset outwardly from the inner face of the clip and spaced apart from each other and transversely perforated, the end piece for the trace extending between the spaced ends and being transversely perforated, said perforation registering with the perforations of the clip, and a pivot passing through the registering perforations, said pivot comprising a plurality of sections, each consisting of a

head and a stem, the stem of the inner section being externally threaded and the stem of the outer section being internally threaded for engaging the first named stem, the inner section having a flat head whose face is flush with the inner face of the clip. 35

3. A hame tug comprising a clip doubled upon itself to form an eye for encircling the hame, the ends of the clip being offset outwardly from the plane of the clip and spaced apart from each other, an end piece 45 for the trace arranged between the spaced ends of the clip, and a pivot traversing the said spaced ends and the trace end, said pivot comprising interengaging sections, the inner section having a flat head whose face is flush with the inner face of the clip. 50

4. A hame tug comprising a clip doubled upon itself to form an eye for encircling the hame, the ends of the clip being offset outwardly from the plane of the clip and 55 spaced apart from each other, an end piece for the trace arranged between the spaced ends of the clip, and a pivot traversing the said spaced ends and the trace end, said pivot having a flat head at the inner end whose face is flush with the inner face of the clip. 60

In testimony whereof I have signed my name to this specification in the presence of two subscribing witnesses.

AMBROSE L. SADDLEMIRE.
